(57) **CLAIM**

The ornamental design for a control panel for a bench scale weighing device, as shown and described.

DESCRIPTION

The file of this patent contains at least one drawing/photograph executed in color, copies of this patent with color drawing(s)/photograph(s) will be provided by the Office upon request and payment of the necessary fee.

FIG. 1 is a perspective view of a control panel for a bench scale weighing device in accordance with a first embodiment of the design;

FIG. 2 is a front view of the control panel of FIG. 1;

FIG. 3 is a top view of the control panel of FIG. 1 with the bottom view being a mirror image thereof;

FIG. 4 is a left side view of the control panel of FIG. 1 with the right side view being a mirror image thereof;

FIG. 5 is another perspective view of the control panel for bench scale weighing device of FIG. 1;

FIG. 6 is a perspective view of a control panel for bench scale weighing device in accordance with a second embodiment of the design;

FIG. 7 is a front view of the control panel of FIG. 6;

FIG. 8 is a top view of the control panel of FIG. 6 with the bottom view being a mirror image thereof;

FIG. 9 is a left side view of the control panel of FIG. 6 with the right side view being a mirror image thereof; and,

FIG. 10 is another perspective view of the control panel for bench scale weighing device of FIG. 6.

The broken lines in the drawings represent unclaimed environmental subject matter and form no part of the claim.
